Primary Examiner—Wallace R. Burke**Assistant Examiner—H. Baynham****[57] CLAIM**

The ornamental design for an electric wire holder, as shown and described.

DESCRIPTION

FIG. 1 is a perspective view of an electric wire holder embodying my new design;

FIG. 2 is a front elevational view thereof;

FIG. 3 is a top plan view thereof;

FIG. 4 is a bottom plan view thereof; and,

FIG. 5 is a side elevational view thereof with the opposite side being a mirror image thereof.

*FIG. 1**FIG. 2**FIG. 3**FIG. 5**FIG. 4*
